UNITED STATES PATENT OFFICE.

LESTER S. KEILMOLTZ, OF DAYTON, OHIO, ASSIGNOR, BY MESNE ASSIGNMENTS, TO
DELCO-LIGHT COMPANY, OF DAYTON, OHIO, A CORPORATION OF DELAWARE.

ELECTRICAL SYSTEM.

Application filed July 11, 1919. Serial No. 310,109.

This invention relates to electrical systems including a storage battery, a dynamo driven by an internal-combustion engine for charging the battery or operable as a motor to start the engine, and ignition apparatus for the engine.

One of the objects of the invention is to control the circuit connections between the dynamo and battery so that below a predetermined engine speed the battery will be automatically disconnected from the dynamo, and that this disconnecting operation, when it does take place, will take place rapidly and in a manner such as to prevent injury to the circuit controlling devices.

A further object of the invention is to provide a circuit controller of improved construction wherein the cost of manufacture has been reduced to a minimum by reason of its simplicity of construction.

Other and further objects and advantages of the present invention will be apparent from the following description, reference being had to the accompanying drawings, wherein a preferred embodiment of the present invention is clearly shown.

In the drawings:

Fig. 1 is a diagrammatic side elevation of an internal-combustion engine directly connected with a dynamo which is shown partly in section, together with a wiring diagram including a diagrammatic side elevation of the controlling device included in the present invention.

Fig. 2 is a front elevation of the controlling device embodying the present invention.

Fig. 3 is a sectional view taken on the line 3—3 of Fig. 5;

Fig. 4 is a right-side elevation of the controlling device looking towards the left;

Fig. 5 is a left-side elevation of the controlling device looking towards the right;

Fig. 6 is a perspective view of the controlling device provided with the cover included in the present invention;

Fig. 7 is a bottom plan view of the cover removed from the controlling device; and

Fig. 8 is a sectional view taken on the line 8—8 of Fig. 6.

In the drawings, 20 designates an internal-combustion engine driving a dynamo 21 which is directly connected with the engine.

Dynamo 21 includes an armature 22, commutator 23, brushes 24 and 25, and field pole pieces 26 and 27. The dynamo is provided with a shunt field 28 connected across the brushes 24 and 25, and with a series field 29, one end of which is connected with brush 25, and the other with dynamo terminal 30. Brush 24 is connected with terminal 31, and brush 25 with terminal 32.

Ignition for the engine is furnished by the agency of the ignition coil 40 which includes primary 41 connected with timer 42, which in turn is connected with ignition terminal 43. The other end of primary 41 is connected with ignition resistance 47 which in turn is connected with ignition terminal 44. Secondary winding 45 is connected at one end with spark plug 46 and grounded at the other end upon the engine.

50 designates a storage battery, the positive side of which is connected with terminal 51 and the negative side with terminal 52.

The controller 60 will now be described. 75 This controller includes a frame 61 of magnetic material supporting a magnet core 62 and an armature post 63. Post 63 supports a pivotally mounted armature 64. A magnetic circuit is formed by members 62, 61, 63, and 64, with a gap between the armature 64 and the core 62. Upon the core 62 is mounted a series magnet winding 65, one end being connected with terminal 67 and the other end connected with terminal 66. 85 The core 62 also supports a shunt magnet winding 68, one end being connected with a terminal 69 and the other end connected with terminal 70.

Terminal 67 is connected with a resilient 90 conductor 71 carrying a non-conducting rubbing-block 72 and a contact 73. Contact 73 is arranged to engage with contact 74 which is connected with terminal 75. A roller 76, pivotally mounted upon the armature 64, 95 engages the rubbing-block 72 when the armature 64 is moved upwardly, actuating the contacts by moving contact 73 into engagement with contact 74. Preferably the conductor 71 carries a resilient conductor 77, 100 carrying at its outer end a contact of arc-withstanding material 78 projecting beyond the outer surface of contact 73, as shown in Fig. 4.

Contact 70 is connected with resilient conducting member 80 having its outer end bent over to form a contact 81 and carrying intermediate its ends a non-conducting rubbing-block 82. Contact 81 is arranged to engage with contact 83 which is connected with terminal 84. A controlling lever 85, pivotally mounted upon the armature post 63, carries a roller 86 which is arranged to engage with the rubbing-block 82 for the purpose of moving the contact 81 out of engagement with the contact 83. As shown in Fig. 5, the pressure of contact 81 against contact 83 is preferably supplemented by introducing a spring 91 between resilient member 80 and frame 61, the spring being insulated from frame 61 by insulating block 92, though it should be understood that spring 91 is not essential and may be omitted.

Lever 85 is provided with a projecting tongue 87 which is arranged to engage the under side of a block 88 of non-magnetic material which is mounted upon the under side of armature 64. The purpose of this block 88 is to prevent a magnetic circuit being directly formed between tongue 87 and lever 85, where these members are made of magnetic material, such as pressed steel. The lever 85 and the armature 64 are preferably mounted upon rod 89, supported by armature post 63, and held in position by means of the bolt 90.

A resilient conductor 100 mounted directly upon the frame 61 is located within the path of motion of the conductor 71 as to be engaged thereby when the contacts 73 and 74 are closed.

The terminals 66, 67, 69, 70, 75 and 84, which have been described, are all mounted on the frame 61 but are insulated therefrom. The frame carries one contact 101 which is grounded thereon. All these terminals, except terminal 69 are connected to the same side of the line, in order to reduce the possibility of short-circuiting the dynamo or battery through the controller 60.

The connections between the dynamo, battery, ignition apparatus, and the controller are as follows: Dynamo terminal 31 is connected with battery terminal 51 by a wire 110. Controller terminals 70 and 75 are connected by bus-bar 112. Controller terminal 84 is connected with generator terminal 32 by a wire 113. Controller terminal 70 is connected with generator terminal 30 by a wire 114. Wire 110 is connected by wire 115 with ignition terminal 43, and by wire 116 with controller terminal 69. Ignition terminal 44 is connected by wire 117 with terminal 101.

The operation of the invention is as follows: To start the engine, the lever 85 is pulled upward to effect engagement of contact 73 with contact 74, of member 71 with

member 100, and the disengagement of contact 81 from contact 83.

The following cranking circuit will then be established: from the positive terminal 51 of the battery 50, through wire 110, generator terminal 31, brush 24, armature 22, brush 25, series winding 29, terminal 30, wire 114, terminal 70, bus-bar 112, terminal 75, contact 74, contact 73, conductor 71, terminal 67, series winding 65, terminal 66, and wire 111 to battery terminal 52. It will be noted that since contacts 81 and 83 are separated that current does not flow out of generator terminal 32 through the conductor 113, and thence through terminal 84, contacts 83 and 81, and thence from terminal 70 to the battery terminal 52 through the circuit described. In this manner the short circuit around the series winding is interrupted so that the dynamo will act as a compound wound motor, the shunt winding 28 being at all times connected across the brushes 24 and 25.

When the starting lever 85 is still in the position described, the following ignition circuit will be established: From the battery terminal 51, through wire 110, wire 115, ignition terminal 43, timer 42, primary 41, resistance 47, terminal 44, wire 117, controller terminal 101, contact 100, conductor 71, terminal 67, winding 65, terminal 66, wire 111, to battery terminal 52.

After the engine has become self-operative it will quickly pick up in speed and will operate the dynamo as a generator to furnish current for battery charging purposes. In order to maintain the circuit connections between the dynamo and battery that current may be delivered to the battery from the dynamo, series magnet winding 65 and shunt magnet winding 68 are utilized. The former winding being a current winding and the latter a voltage winding, the armature 64 is maintained in attracted position with respect to magnet core 62 as long as the output of the dynamo exceeds a predetermined value.

With the armature 64 maintained magnetically in circuit closing position, the starting lever 85 may be released, causing the contacts 81 and 83 to be brought together to short-circuit the series-field winding 29. The dynamo will then act as a shunt-wound generator to charge the battery.

In case the speed of the engine falls off to such a low value that the voltage of the generator falls below a value sufficient to oppose the battery voltage, the current from the battery will tend to flow toward the generator to drive the same as a motor. When this occurs there will be a reversal of current in the series magnet winding 65 which will tend to create magnetism in opposition to that created by the voltage winding 68. When this occurs the attractive

force upon the armature 64 will not be sufficient to maintain it in circuit closing position against the force exerted by the resilient conducting member 71 upon the roller 76.

5 It will be noted that the resilient conducting member 71 exerts a force or pressure on armature 64 in a substantially uniform direction at right angles to the length of the resilient member, and that when the armature 10 is in its attracted or contact operating position the line of action of the spring pressure, which passes through the point of contact with roller 76, is close to the fulcrum of the armature and is disposed at an acute 15 angle to the lever arm passing through the fulcrum and the point of contact with resilient member 71. The relation of the armature 64 and roller 76 to the rubbing-block 72 is such that if there is therefore 20 any tendency for the magnet to release its magnetic grip upon its armature 64, this tendency will give the spring conducting member 71 an opportunity to increase the gap between armature 64 and the core 62.

25 Any increase in the gap will make it the more difficult for the magnet to maintain the armature 64 in attracted position. At the same time, as the gap increases, the line of action of the spring force will recede 30 from the fulcrum, and the leverage of the spring force exerted by member 71 upon the roller 76, or the moment of this force about the fulcrum pin 89, will also increase. Although the spring force in resilient member 35 71 is decreasing all the time that roller 76 is moving upwardly, the relation between the roller 76 and block 72 is such that during the upward movement of roller 76 the lever arm of the spring force exerted by member 40 71 increases at a more rapid rate than the decrease of said spring force. Therefore if there is any tendency for the magnet to release its grip upon the armature and to decrease the spring pressure between contacts 45 73 and 74 to any substantial degree by any slight upward movement of the roller 76, this tendency will be assisted in increasing amounts as the gap between the armature and the magnet core increases. Therefore, 50 if the spring tension in member 71 is relaxed due to diminution of attractive power of the magnet to any substantial degree, the armature 64 will be almost instantly moved out of attracted position under the action of the 55 spring pressure in member 71, and the contacts 73 and 74 which carry all of the charging current will be almost instantly separated. Therefore it is apparent that these contacts 73 and 74 will either be held together with sufficient pressure to insure a good contact or else they will be separated with sufficient rapidity to prevent arcing.

55 Arcing at the main contacts 73 and 74 is also prevented by virtue of the non-arcing, or arc-with-standing, contact 78, shown in

Fig. 4, which engages contact 74 before contact 73 engages said contact 74, and remains in engagement with the contact 74 for an instant after the separation of contact 73 from contact 74.

Referring now more particularly to Figs. 6, 7, and 8, numerals 61^a and 61^b designate respectively the vertical and horizontal portions of the frame 61. These portions are braced by means of the brace 61^c. Normally the frame 61 is mounted upon any suitable support, such as a switchboard by attaching the vertical portion 61^a to the switchboard. In order to protect the controller from dust and from accidental injury as much as possible a cover 160 is provided. Cover 160 is substantially U-shaped in cross-section, the branches of the U being formed by the sides of the cover 161 and 162. These sides 161 and 162 are provided with beads 163 and 164 which are substantially parallel and are adapted to be engaged by the parallel side edges of the vertical portion 61^a of the frame 61. Adjacent the upper edge portion of the cover 160 the side portions 161 and 162 are provided with a continuous bead 165 which is adapted to be engaged by the edge of the horizontal portion 61^b of the frame 61. This bead 165 is bent over and terminates in the edge 167 which contacts with the horizontal portion 61^b to form a substantially dust-proof joint.

Before the cover 160 is placed upon the controller frame 61, the relative position of the side portions 161 and 162 is as shown in full lines in Fig. 7. In this position the distance between the beads 163 and 164 is slightly less than the width of the vertical portion 61^a of the frame 61. In placing the cover 160 upon the frame 161, the side portions 161 and 162 are sprung apart so as to take the positions 161^a and 162^a respectively, shown by dotted line in Fig. 7. In this manner the cover 160 is sprung in place upon the frame 61, so that the beads 163 and 164 are yieldingly pressed against the edges of the vertical portion 61^a of the frame 61. The construction of the bead 165 is such that it will be necessary to spring the upper edge portion of the side 161 and 162 in order that the bead 165 may be engaged by the edges of the horizontal portion 61^b of the frame 61. The inter-locking relation of bead 165 with portion 61^b is shown in Fig. 8.

An additional bead 166 is provided as shown in Fig. 6 for purposes of ornamentation.

It is apparent that this cover provides an enclosure which prevents dust from descending upon the working parts of the controller and will prevent accidental injury thereto. This enclosure also hides from view all of the working parts of the controller except the manually operable lever 85. By hiding all of the parts except the member to be

operated, any confusion which would be likely to occur in the operation of the controller is eliminated.

Another feature of the invention which tends to simplicity of construction is the inter-locking arrangement of the terminals and switch members and insulating members which comprise the controller. This feature is clearly illustrated in Fig. 3. Certain portions of the terminals 66, 67, 69 and 70 are square in cross-section. Terminals 66 and 69 are mounted directly upon insulating block 170. Terminals 67 and 70 are mounted in contact with switch elements 71 and 80 respectively, which have their fixed ends bent up along one of the plane surfaces of the said terminals 67 and 70. An insulating block 171 is constructed so as to have its two opposite edges in engagement with adjacent parallel plane surfaces of terminals 69 and 66, and is notched at 172 and 173 so as to engage the corners of contacts 71 and 80 respectively. Terminals 66, 67, 69 and 70 hold the insulating block 170 and the controller conducting members 71 and 80 in position, and only one rivet 174 is necessary to maintain the block 171 in position. Terminals 66, 67, 70 and 69, and conductors 71 and 80 are thereby prevented from turning whenever any nuts are screwed onto or unscrewed from the threaded ends of these terminals.

The insulating block 175 is provided with a surface which locks the armature post 63 in position, and the insulating block 176 is of such width as to engage the edges of switch terminals 74 and 83, and to maintain these terminals in correct position with respect to the conducting members 71 and 80 respectively. A post 177 is arranged to secure the insulating blocks 175 and 176 upon the frame 61, and serves also as a stop member limiting the desired movement of the lever 85.

While the form of mechanism herein shown and described constitutes a preferred form of embodiment of the invention, it is to be understood that other forms might be adopted, all coming within the scope of the claims which follow.

What I claim is as follows:

1. An electrical controller which comprises in combination, an L-shaped magnetic frame, a plurality of switch mechanisms carried by one leg of said magnet frame, a core carried by the frame and disposed in parallel relation with respect to said leg, a magnet winding surrounding the core, an armature pivotally supported by the leg, said armature being adapted to bridge the gap between the leg and core and control one of said switch mechanisms, and a manually operated lever pivotally carried by said leg for moving said armature adjacent the magnet core and releasable from the armature while

permitting the armature to be maintained in a certain position by the magnet, said lever being arranged to control another of said switch mechanisms.

2. An electrical controller which comprises in combination, a magnetizable frame including a magnet core, a magnet winding surrounding said core, an armature supported by the frame, switch mechanism operated by the armature, said switch mechanism and including a plurality of contacts and means exerting a yielding pressure on the armature tending to move it out of contact operating position, the line of action of the pressure passing close to the fulcrum of the armature in its contact operating position and receding from the fulcrum as the lever moves out of its contact operating position, a lever pivotally mounted on the frame and manually operable for moving said armature adjacent said magnet core and releasable from the armature while permitting the armature to be maintained in a certain position by the magnet, and other switch mechanism operated by the lever.

3. An electrical controller which comprises in combination, an L-shaped magnet frame, a core carried by one leg of the frame and disposed in parallel relation with respect to the other leg of said frame, a magnet winding surrounding said core, an armature pivotally supported by the frame and having its fulcrum disposed between the core and said other leg, switch mechanism operated by the armature and including a plurality of contacts and means exerting a yielding pressure on the armature tending to move it out of contact operating position, the line of action of the pressure passing close to the fulcrum of the armature in its contact operating position and receding from the fulcrum as the lever moves out of its contact operating position, a lever pivotally mounted on the frame and manually operable for moving said armature adjacent said magnet core and releasable from the armature while permitting the armature to be maintained in a certain position by the magnet, and switch mechanism for controlling another circuit operated by the lever.

4. An electrical controller, which comprises in combination, an L-shaped magnetizable frame, a core carried by one leg of the frame and located parallel to the other leg, a magnet winding surrounding said core, a magnetizable fulcrum post connected with and extending from the said other leg toward the core, an armature pivotally supported by the post and movable for bridging the gap between the post and core, a lever pivotally supported by the post for moving the armature toward the core and releasable from the armature to permit the magnet to retain the armature, and switches located on opposite sides of the fulcrum post and supported by

said magnet frame and operated respectively by the armature and lever.

5. In an electrical controller, in combination, a supporting plate having openings therethrough, current-conducting members of non-circular outline mounted on one side of the plate, each having a reduced portion, extending through said opening, said portion being circular in cross-section through-

out the entire length of said portion and 10 screw-threaded to receive a nut for clamping said member to the plate, and an insulating block between two of said members and conforming to and engaging a non-circular portion of each member for preventing said 15 members from turning.

In testimony whereof I affix my signature.

LESTER S. KEILHOLTZ.
